CLAIM

We claim the ornamental design for an access structure, as shown and described.

DESCRIPTION

FIG. 1 is a top-front perspective view of a first configuration of an access structure, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a top-rear perspective view of thereof.

FIG. 9 is a top-front perspective view of a second configuration of an access structure, showing our new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and

FIG. 16 is a top-rear perspective view of thereof.

The broken lines in the drawings depict portions of the access structure that form no part of the claimed design.

1 Claim, 12 Drawing Sheets
